INVENTOR

Aaron R. Chisholm
BY Charles R. Searle

ATTORNEY

UNITED STATES PATENT OFFICE.

ARRON R. CHISHOLM, OF EAST ORANGE, NEW JERSEY.

VANITY CASE.

Application filed June 1, 1927. Serial No. 195,608.

The invention relates to receptacles adapted to contain face powder and the like for personal use, and the object of the invention is to provide a case of simple and inexpensive construction adapted to contain a charge of loose powder presented for convenient access in the small quantities required, while holding the bulk of the charge against accidental delivery due to the changes in position to which articles of this character are necessarily liable.

The invention consists in certain novel features of construction and arrangements of parts by which the above objects are obtained, to be hereinafter described and claimed.

The accompanying drawings form a part of this specification and show the invention as it has been carried out in practice.

Figure 1 is an edge view of the case with the cover in place.

Figure 2 is a plan view of the body of the case with the cover removed.

Figure 3 is a plan view showing the interior of the cover.

The remaining figures are on an exaggerated scale.

Figure 4 is a diametrical section through the complete case.

Figure 5 is a corresponding section of a ring or bezel forming part of the cover.

Figure 6 is a similar section through a diaphragm or partition forming part of the body of the case.

Similar reference numerals indicate the same parts in all the figures.

The main portion of the body of the case is a shell of sheet metal cut and shaped by suitable dies to the form shown, having an

outwardly domed or convex bottom 10 and a vertical annular flange 11 with an off-set bead 12 at the junction of those members.

The cover is similarly formed having a top 13 and a vertically depending flange 14

with a bead 15 at their junction. The flange 14 incloses the flange 11 closely but with liberty to permit the easy separation of the cover and body, and the bead 12 serves as a seat for the rim of the flange 14 when the cover is applied. The top 13 of the cover is preferably domed outwardly to correspond symmetrically with the bottom 10.

In the interior of the cover is a mirror 16

of circular form held in place by a ring or bezel 17, which is forced into position within the flange 14 and held therein by the strong frictional contact thus induced.

A horizontally disposed partition or diaphragm in the upper portion of the body serves with the latter as a receptacle for the powder and comprises a cylindrical flange or lip 18 matching closely to and within the flange 11 and having a rounded annular shoulder 19 at the top from which extends a depressed conical deck 20 having a circular central aperture 21.

The space between the deck 20 and mirror 16 serves as an inclosure for the powder puff or pad, not shown, when the cover is placed on the body, and the space between the deck 20 and bottom 10 serves as an annular pocket in which the charge is retained in the various angular positions assumed by the case in service.

The charge of loose powder is supplied through the aperture 21 and is presented thereto for easy access by the puff as will be understood.

It will be noted that all the parts, excepting the mirror 16 are of thin sheet metal easily formed by dies and stamping methods, and are held in position by frictional engagement with each other without other fastening means, and also that all the parts are easily and quickly assembled with little labor, thus providing an efficient and attractive case at a minimum of production cost.

Instead of employing the removable cover held to the body telescopically, as shown, the cover and body may be joined by a hinge or other preferred means.

The dished form of the bottom 10 immediately below the aperture 21 when the case is held horizontally tends to collect the powder at that point easily accessible to the puff, as will be noted.

I claim:

The vanity case described comprising a circular body portion having a dished bottom and an annular vertical flange thereon with an outwardly projecting bead at the junction of said vertical flange and bottom and formed integrally with said vertical flange and bottom, a diaphragm in said body consisting of a vertical lip matching closely

- within said vertical flange and a downwardly inclined conical deck integral with said lip and having a central aperture therein, forming with said bottom an annular pocket, and
- 5 a circular cover portion having a top and an annular depending flange thereon integral therewith and adapted removably to inclose and engage said vertical flange and to seat on said head, a mirror in said cover and a bezel for holding said mirror in place by 10 frictional engagement with said depending flange.
- In testimony that I claim the invention above set forth, I affix my signature hereto.

ARRON R. CHISHOLM.

within said vertical flange and a downwardly inclined conical deck integral with said lip and having a central aperture therein, forming with said bottom an annular pocket, and 5 a circular cover portion having a top and an annular depending flange thereon integral therewith and adapted removably to inclose and engage said vertical flange and to seat on said head, a mirror in said cover and a bezel for holding said mirror in place by 10 frictional engagement with said depending flange.

In testimony that I claim the invention above set forth, I affix my signature hereto.

ARRON R. CHISHOLM.

DISCLAIMER.

1,651,193.—*Arron R. Chisholm*, East Orange, N. J. VANITY CASE. Patent dated November 29, 1927. Disclaimer filed November 14, 1928, by the *patentee*.

Heraby enters this disclaimer of that part of the claim in said specification which is in the following words, to wit: "with an outwardly projecting head at the junction of said vertical flange and bottom and formed integrally with said vertical flange and bottom."
